CLAIM

The ornamental design for an earphones with charging case, as shown and described.

DESCRIPTION

FIG. 1 is a front, bottom and left side perspective view of an earphones with charging case, showing my new design; FIG. 2 is a rear, top and left side perspective view thereof; FIG. 3 is a front, bottom and left side perspective view of the earphones with charging case, shown in an opened state; FIG. 4 is a front, top and left side perspective view thereof; FIG. 5 is a front view of the earphones with charging case, shown in a closed state; FIG. 6 is a rear view thereof; FIG. 7 is a left side view thereof; FIG. 8 is a right side view thereof; FIG. 9 is a top plan view thereof; FIG. 10 is a bottom plan view thereof; FIG. 11 is a rear, bottom and right side perspective view of an earphones of the earphones with charging case, shown separately to show aspects of the design that are not visible when combined;

FIG. 12 is a front, top and left side perspective view thereof; FIG. 13 is a front view thereof; FIG. 14 is a rear view thereof; FIG. 15 is a left side view thereof; FIG. 16 is a right side view thereof; FIG. 17 is a top plan view thereof; and, FIG. 18 is a bottom plan view thereof.

The broken lines shown in the drawings illustrate portions of the earphones with charging case that form no part of the claimed design.
